(57) **CLAIM**

The ornamental design for a clog, as shown and described.

DESCRIPTION

FIG. 1 is a front, right and top perspective view of a clog, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled "9" in FIG. 2.

A clog for the left foot is a mirror image of the clog for the right foot as shown in FIGS. 1 to 8 and is also claimed.

The broken lines shown in the drawings are included for the purpose of illustrating portions of the clog that form no part of the claimed design. In addition, the dot-dash lines in FIGS. 2 and 9 are for the purpose of showing the areas of enlargement and form no part of the claimed design.
